BATTERY POWER PACK

Louis H. Roth, St. Albans, N.Y.

Application May 5, 1958, Serial No. 50,769

Term of patent 14 years

(Cl. D26—15)

Fig. 1 is a front perspective view of a battery power pack, showing my new design, the opposite side being substantially a mirror image thereof;

Fig. 2 is a rear elevational view, the carrying strap being omitted for convenience in illustration; and

Fig. 3 is a fragmentary side elevational view thereof, a portion being broken away to show the knobs.

The dominant features of my design reside in the portions shown in full lines.

I claim:

The ornamental design for a battery power pack, as shown and described.
